UNITED STATES PATENT OFFICE.

ALBERT O. BUCKIUS, JR., OF CHICAGO, ILLINOIS, ASSIGNOR TO THE NATIONAL
MALLEABLE CASTINGS COMPANY.

JOURNAL-BOX-SECURING MECHANISM.

1,093,170.

Specification of Letters Patent. Patented Apr. 14, 1914.

Application filed April 24, 1913. Serial No. 763,319.

To all whom it may concern:

Be it known that I, ALBERT O. BUCKIUS, Jr., a citizen of the United States, residing at Chicago, Cook county, Illinois, have invented new and useful Improvements in Journal-Box-Securing Mechanism, of which the following is a specification, reference being had to the accompanying drawings, in which—

10 Figure 1 is a side elevation of a journal box and of a portion of a truck side frame embodying my invention; Fig. 2 is a section on the broken lines II—II of Fig. 1, showing the side frame in section with the journal box in plan; Fig. 3 shows in side elevation the application of my invention to a journal box of the Master Car Builders' type; Fig. 4 is an end elevation of the construction shown in Fig. 3; and Fig. 5 is a 20 bottom view thereof.

My invention relates to the securing of journal boxes to truck side frames and is an improvement on the type of construction shown in my Patent 1,023,805 dated April 25, 1912.

My improvement consists in providing a structure adapted for use with either the journal box of the type shown in my patent aforesaid, or with a journal box of the Master Car Builders' type, so that journal boxes of these types may be freely interchanged.

Referring to the drawings, I have shown in Figs. 1 and 2 a journal box A, of the type shown in my patent aforesaid, secured to a 35 portion of a side frame 2 of a car truck. The side frame 2 has at its end an overhung extension 3 to receive and rest on the journal box A. The lower face 4 of this projection is preferably horizontal to fit the 40 top of the box, and the end of the side frame has a vertical bearing face 5 substantially at right angles to the face 4, the box fitting in the angle between the two faces 4 and 5. Twisting and endwise movement 45 of the box is prevented by the flanges 6, 6' which bear respectively against the outer sides of the ribs 7 on the face 5 and the lugs 8 extending downwardly from the extension 3. The box A is secured to the frame by 50 the curved strap bolt 9, the head of which fits into the recess 10 on the frame, and the threaded end into an aperture 11 in the extension 3, and is secured therein by the holding nut 12, which bears against the upper

surface of the extension 3. The box A has 55 a groove 13 in which bolt 9 fits and a hook 14, which acts as a retainer for the bolt 9.

In Figs. 3, 4 and 5, I have shown a journal box B of the Master Car Builders' type, which is interchangeable with the type of 60 box shown in Figs. 1 and 2. The box B is secured to the side frame by the bolts 15 and 16 and by the shim 17 and plate 18. The bolts 15 and 16 fit in apertures 11 and 19 in the extension 3. The bolt 16 is preferably countersunk in the extension, so that the bolts 15 and 16 may be of the same length. The shim 17 has a bearing on the bottom of the box B. The plate 18, which underlies the shim 17, has a hooked portion 65 21 coöperating with a recess 22 in the frame. Both the shim 17 and the plate 18 are apertured for the bolts 15 and 16 and are held against the bottom of the box B by the retaining nuts 23 and 24. At the sides of the 70 box B and at its top and bottom are the usual V-shaped projections 25, 25', and webs 26, 26' connect the projections 25, 25' respectively. The projections 25 fit in between the ribs 7 and against the vertical 75 face 5, and the webs 26 also provide bearings against the inner faces of the ribs 7, while the upper projection 25' fits in between the depending lugs 8 of the extension 3, thus holding the box against twisting or 80 endwise movement.

It will be seen that with my improved construction the ribs 7 and lugs 8 prevent boxes of either type from twisting or from endwise movement, since with the type of 85 box shown in Figs. 1 and 2 the flanges 6, 6' grip the outer side faces of the ribs and lugs while with the type of box shown in Figs. 3, 4 and 5 the projections 25, 25' and webs 26 bear against the inner side faces of 90 the ribs and lugs.

My invention is of great advantage since, if a car is equipped with journal boxes of the type shown in Figs. 1 and 2, and one of the boxes breaks, it can be replaced without 95 delay by an M. C. B. box.

It is obvious that many changes may be made in the construction which I have shown and described herein without departing from my invention.

It is to be understood that with the M. C. B. box the plate 18 may be secured to the frame by any suitable means such as bolts,

in which case the plate may be made without the hooked portion 21. It is also to be understood that the shim 17 may be inserted between the box and the extension 3 instead of between the box and the plate 18 in case it is desired to raise the frame and the car higher when either the bolster springs or the frame have taken a permanent set.

10 What I claim is:

1. A truck side frame having two bearing surfaces at an angle to each other, one of said bearing surfaces having upstanding ribs adapted to receive between them V-shaped projections on a journal box of the Master Car Builders' type, the said ribs being adapted to enter between flanges upon a journal box of another type, seats for bolts to secure a box of the Master Car Builders' type, and an additional seat coöperating with one of the first-named seats to receive between them a strap to secure a journal box of a different type.

2. In journal box securing mechanism, a truck side frame having a journal box seat, a bolt hole arranged for securing in said seat journal boxes having differently dimensioned bearings for the journal box seat, and a second bolt hole arranged to assist in securing in said seat a journal box of the Master Car Builders' type.

3. A truck side frame having two bearing faces at an angle to each other, a journal box seated on said faces, and a strap arranged to draw and hold the box against said faces, one of said faces having ribs adapted to receive therebetween V-shaped projections on the side of a box of the Master Car Builders' type.

40 4. A truck side frame having two bearing faces at an angle to each other, one of said faces being adapted to take about V-shaped projections on a box of the Master Car Builders' type, and bolt-seating apertures 45 for receiving bolts to secure said box to the frame, one of said apertures being adapted

to receive a strap arranged to draw and hold a box of another type against said faces.

5. In a journal box securing mechanism, a truck side frame having a journal box seat, 50 said seat being adapted to secure therein a journal box having a wider seating surface than that of the Master Car Builders' type, said seat being arranged to receive therein the narrower bearing of a journal box of the 55 Master Car Builders' type, and apertures for receiving bolts to secure either of said boxes to the frame.

6. In a journal box securing mechanism, a truck side frame having a journal box 60 seat, a journal box having projections on both of its sides, vertically disposed ribs on said seat coöperating with the said projections on both sides of the box to prevent twisting and endwise movement of the box, 65 and bolting means for holding the said box in its position in said seat.

7. In journal box securing mechanism, a side frame having a journal box seat, a journal box, and means for supporting the journal box comprising a plate having at one end a hooked portion coöperating with a recess in the frame and bolting members securing together the other end of the plate, the journal box and the side frame.

75 8. A truck side frame having two bearing surfaces at an angle to each other, and adapted to receive a journal box of the Master Car Builders' type, or a box of a different type, one of said seats having upstanding 80 ribs adapted to take about V-shaped projections on a side of the Master Car Builders' box, said ribs being adapted to lie between flanges upon a box of a different type, means for restraining either type of box from 85 twisting and endwise movement, and means, comprising bolts, for securing either type of box to the frame.
